UNITED STATES PATENT OFFICE

JOSEPH C. CLARK, OF COLUMBUS, OHIO, ASSIGNOR TO THE OHIO STATE STOVE CORPORATION, OF COLUMBUS, OHIO, A CORPORATION OF OHIO

DESIGN FOR A COOKING STOVE OR ARTICLE OF SIMILAR NATURE

Application filed February 28, 1931. Serial No. 38,874. Term of patent 14 years.

To all whom it may concern:

Be it known that I, JOSEPH C. CLARK, a citizen of the United States, residing at Columbus, in the county of Franklin, and State of Ohio, have invented a new, original and ornamental Design for a Cooking Stove or Article of Similar Nature, of which the following is the specification, reference being had to the accompanying drawings, forming a part hereof.

I claim:

The ornamental design for a cooking stove or article of similar nature, as shown.

JOSEPH C. CLARK.
